MANIFOLDING

Carl W. Brenn, Montclair, N. J., assignor to Auto-graphic Register Company, Hoboken, N. J., a corporation of New Jersey

Application September 12, 1929, Serial No. 392,006

16 Claims. (Cl. 282—12)

This invention relates to manifolding, and more particularly, to a pack of worksheets to be used in making original and duplicates thereof.

In my copending application, Serial No. 5 221,912, filed September 26, 1927, there is disclosed a manifolding pack having means for holding a plurality of superposed worksheets with interleaved carbon sheets in accurate registration preparatory to, and during the operation of, type-writing on the strips, the strips being continuous and comprising a succession of printed forms and being folded zig-zag at form-length intervals to form a pack. The said means for holding the strips in my said application were so disposed 10 with relation to the line of severance between forms as to be rendered inoperative when the pile of strips were severed so as to produce a plurality of sheets of form-length after the typewriting operation was performed.

With some kinds of work, it is desired to complete the filling-in of some of the forms after a set of forms has been separated from the strips. Heretofore, this has necessitated the collation and alignment of the forms to be written upon 15 and their carbon sheets unless the worksheet strips and carbonsheet strips were formed of one web folded longitudinally which is not always feasible and which adds to the cost.

A feature of the present invention is the provision of means for separately holding together the group of individual printed worksheets and their carbons which are to be written upon after they have been severed from the strips, independently of the means which holds all of the strips 20 of the pile together so that when a set of superposed forms is severed from the strips, those forms and their carbons which are to be further written upon are held together while the others and their carbons will be free or separate to be 25 filed or otherwise disposed of.

Other features and advantages will hereinafter appear.

In the accompanying drawings which illustrate one embodiment of this invention, that at 30 present preferred—

Figure 1 is a perspective view of a manifolding pack made in accordance with this invention.

Fig. 2 is a longitudinal section taken through the pile of worksheets of which the pack in Fig. 1 35 is formed.

Fig. 3 is a transverse sectional view taken on line 3—3 and showing the means for holding the sub-group together independently of the other strips.

Fig. 4 is a transverse sectional view taken on

the line 4—4 of Fig. 1, showing the means for holding all of the strips of the pile together.

Fig. 5 is a view showing all of the strips held together by the staples which are located in the heading of the forms. 5

Fig. 6 is a longitudinal section of the pack shown in Fig. 5.

Fig. 7 is a transverse section taken on the line 7—7 Fig. 5.

Fig. 8 is a plan view of one of the intermediate 10 strips on the pack shown in Fig. 5.

Fig. 9 is a similar view of one of the outside strips, i. e., either the top or bottom strip.

Fig. 10 is a sectional view of another modified form of the invention. 15

As shown in the accompanying drawings, the manifolding pile comprises a plurality of superposed continuous worksheets 10 each of which may have a continuous succession of printed forms 11. Interleaved between each two adjacent 20 worksheet strips 10 is a carbon strip 12, so that writing performed on the top strip 10 will be reproduced on the under strips 10 through the medium of the carbon strips 12.

To receive said writing operations, the worksheet strips 10 are placed in proper superposed relation one above the other with the printed forms 11 on one strip registering with those on the other strip or strips. 25

To hold the worksheet strips 10 in said proper 30 superposed registering relation and to hold the carbon strips in their proper positions relative to the worksheet strips after the strips are superposed, they are secured together by suitable means placed at intervals along the pile of strips. 35 Preferably, these means comprise staples 13 which extend through all of the strips of the pile and have their legs 14 bent over at one side to hold the staples in place against removal.

After a set of forms on the worksheet strips 40 10 has been written upon, it is severed from the succeeding set in the pile of strips along lines of perforations 15, separating one form thereon from the next, and, in the form shown herein, being constituted by perforations 16. 45

So that the staples 13 will become successively inoperative to hold the remaining strips of the pile together, or to hold the severed sets together as set after set of forms have been written upon and severed from the pile, the staples 13 50 50 are preferably located directly on the lines of severance 15, so that, by tearing the strips of the pile along a line of severance 15, the staple on that line will become detached from both the severed form and the adjacent ends of the strips. 55

This permits the written forms to be handled as desired, and to be distributed to different points as well as permitting the resulting carbon sheets to be taken from between the worksheets 5 without the necessity of performing any operation other than severing the strips into form-lengths.

The pile of strips 10 is usually initially written upon in a typewriting machine where all the 10 writing which can be performed at that time is accomplished. However, in some instances, especially in connection with public service work, it is desired to perform further writing on certain of the forms 11 at a later time, for instance, 15 to report what was done in accordance with the orders which may be written on the typewriter. Heretofore, it was necessary to pin, or otherwise fasten, together those of the forms with their interleaved carbon sheets which were to 20 be subsequently written upon to keep them in registration to receive these subsequent writing operations.

In accordance with the present invention, however, these forms which are to be subsequently written upon are initially, that is to say, when the pile of strips is manufactured, fastened together by suitable means. Preferably, these suitable means comprise wire staples 17 which, in the form shown in Fig. 2, secure worksheet strips 10a, 10b and 10c together with their interleaved carbon strips and leave the strip 10d with its overlying carbon strip unattached by the staple 17.

Hence, when the pile of strips 10 is severed 35 along the lines of severance 15, the staple 13 becomes inoperative to hold the strips 10a, 10b, 10c and 10d together and leaves the severed forms of the strip 10d with its overlying carbon free of the strips 10a, 10b and 10c, so that the 40 form of the strip 10a may be filed away, its carbon strip destroyed, and the forms of the strips 10a, 10b and 10c held together with their interleaved carbon sheets by the staple 17 and in proper alignment so that writing performed at 45 certain places on the top form will be reproduced on exactly the same place on the under forms.

After the forms on the strips 10a, 10b and 10c have received their final writing operations, it is desired to separate them, remove the carbon 50 strips from between them, and distribute them to various places. To permit this to be done without necessitating the straightening out of the legs 18 of the staple 17, the strips held together by the staple 17 are provided with a short 55 line of perforations 19 extended beyond both legs of the staple 17. Thus, to separate these forms, it is merely necessary to pull them apart one at a time, tearing the sheet along the line of perforations 19.

60 Thus, it will be seen, the present invention provides a manifolding pile having two separate means for holding the strips together, one of said means holding a group of strips together and the other of the means holding all of the strips 65 together, so that at two separate times and under two different conditions the strips held together may receive writing operations.

This invention also embraces the provision of the staple in the body of the form—that is to 70 say, so that all of the forms are held together by the staple as shown in Figs. 5 to 9, inclusive. In this form of the invention, the staple 20 is located adjacent the line of perforations 15 but not on it. Thus, when a set of written forms are 75 torn from the pile of strips along the line of

perforations 15, a complete booklet is provided which may receive further writing operations and transfer these operations to the under-copies through the intermediate carbon sheets.

In practice, this booklet is passed along from 5 station to station in the routing of the work and at some of the stations one of the strips 10a, 10b, 10c, or 10d is removed.

To permit any one of these strips to be removed from the pile, the intervening strips 10b and 10c are provided with additional lines of perforations 21 just below the staple 20, and the strip to be removed may be torn along the line of perforations 21 for that purpose. The top and bottom strips 10a and 10d need not have 15 perforations similar to the perforations 21 because these may be torn off directly from the staples, and to facilitate this, the strips 10a and 10d may have short lines of perforations 22 on which the staple 20 lies, as indicated in Fig. 9, 20 like the perforations 19 for the staple 17 in the form of the invention shown in Figs. 1 to 4.

By not having the line of perforations 21 on the top and bottom strips 10a and 10d, danger of the pile of strips being torn along the line of perforations 21 instead of the line of perforations 15 is avoided. To further avoid this, the intervening carbon strips 12a, 12b and 12c may be prepared without the lines of perforations 21, as shown in Fig. 10.

Variations and modifications may be made within the scope of this invention and portions of the improvements may be used without others.

Having thus described the invention, what is claimed as new and for which it is desired to obtain Letters Patent, is:

1. A manifolding pile comprising a plurality of continuous worksheet strips each having a succession of forms or sheet lengths separated by lines of severance; a continuous carbon sheet interleaved between each two adjacent worksheet strips; means located at intervals along the pile of superposed strips at the lines of severance for securing all of the strips of the pile together in desired relation with the lines of severance of the several strips in registration, until the pile is severed along said lines to remove a set of written forms; means located at intervals along the pile of strips for securing less than the total number of strips together in desired relation, said second-named means being located between the successive lines of severance so as to hold certain of the worksheets and interleaved carbon collated together subsequent to the severance of the set of form-lengths from the superposed strips; and sheet weakening means in the worksheets whereby one may be separated from the others of the worksheets constituting the group which is secured together by the second-named means.

2. A manifolding pile comprising a plurality of continuous worksheet strips each having a succession of forms or sheet lengths separated by lines of severance; a continuous carbon sheet interleaved between each two adjacent worksheet strips; means located at intervals along the pile of superposed strips at the lines of severance for securing all of the strips of the pile together in desired relation with the lines of severance of the several strips in registration, until the pile is severed along said lines; and means located at intervals along the pile of strips for securing less than the total number of strips together in desired relation, said second-named means being located between the successive lines of severance so as to hold certain of the worksheets and inter-

leaved carbon collated together subsequent to the severance of the set of form-lengths from the superposed strips.

3. A manifolding pile comprising a plurality of 5 continuous worksheet strips each having a succession of forms or sheet lengths separated by lines of severance; a continuous carbon sheet interleaved between each two adjacent worksheet strips; staples located at intervals along the pile 10 of superposed strips at the lines of severance for securing all of the strips of the pile together in desired relation with the lines of severance of the several strips in registration, until the pile is severed along said lines; and means located at intervals along the pile of strips for securing less than the total number of strips together in desired relation, said means being located between the successive lines of severance so as to hold certain of the worksheets and interleaved carbon together after the set of form-lengths has been severed from the superposed strips.

4. A manifolding pile comprising a plurality of continuous worksheet strips each having a succession of forms or sheet lengths separated by 25 lines of severance; a continuous carbon sheet interleaved between each two adjacent worksheet strips; means located at intervals along the pile of superposed strips at the lines of severance for securing all of the strips of the pile together in 30 desired relation with the lines of severance of the several strips in registration, until the pile is severed along said lines; and staples located at intervals along the pile of strips for securing less than the total number of strips together in desired relation, said staples being located between the successive lines of severance so as to hold certain of the worksheets and interleaved carbon together after the set of form-lengths has been severed from the superposed strips.

40 5. A manifolding pile comprising a plurality of continuous worksheet strips each having a succession of forms or sheet lengths separated by lines of severance; a continuous carbon sheet interleaved between each two adjacent worksheet strips; staples located at intervals along the pile 45 of superposed strips at the lines of severance for securing all of the strips of the pile together in desired relation with the lines of severance of the several strips in registration, until the pile is severed along said lines; and other staples located at intervals along the pile of strips for securing less than the total number of strips together in desired relation, said other staples being located between the successive lines of severance so as to hold certain of the worksheets and interleaved carbon collated together subsequent to the severance of the set of form-lengths from the superposed strips.

60 6. A manifolding pile comprising a plurality of continuous worksheet strips each having a succession of forms or sheet lengths separated by lines of severance; a continuous carbon sheet interleaved between each two adjacent worksheet strips; staples located at intervals along the pile 65 of superposed strips at the lines of severance for securing all of the strips of the pile together in desired relation with the lines of severance of the several strips in registration, until said pile is severed along said lines; other staples located at intervals along the pile of strips for securing less than the total number of strips together in desired relation, said other staples being located between the successive lines of severance so as to hold certain of the worksheets and interleaved carbon collated together subsequent to the sever-

ance of the set of form-lengths from the superposed strips; and sheet weakening means in the worksheets whereby one may be separated from the others of the worksheets constituting the group which is secured together by the second-named staples.

7. A manifolding pile comprising a plurality of continuous worksheet strips each having a succession of forms or sheet lengths separated by lines of severance; a continuous carbon sheet interleaved between each two adjacent worksheet strips; means located at intervals along the pile of superposed strips at the lines of severance for securing all of the strips of the pile together in desired relation with the lines of severance of the several strips in registration, until the pile is severed along said lines; staples located at intervals along the pile of strips for securing less than the total number of strips together in desired relation, said staples being located between the successive lines of severance so as to hold certain of the worksheets and interleaved carbon collated together subsequent to the severance of the set of form-lengths from the superposed strips; and lines of perforations in the worksheets constituting the group which is secured together by the second-named staples on which lines the latter are located and along which said worksheets may be torn from the staple.

8. A manifolding pile comprising a plurality of continuous worksheet strips each having a succession of forms or sheet lengths separated by lines of perforations; a continuous carbon sheet interleaved between each two adjacent worksheet strips; staples located at intervals along the pile of superposed strips at the lines of perforations for securing all of the strips of the pile together in desired relation with the lines of perforations of the several strips in registration, until the pile is severed along said lines; and means located at intervals along the pile of strips for securing less than the total number of strips together in desired relation, said means being located between the successive lines of severance so as to hold certain of the worksheets and interleaved carbon collated together subsequent to the severance of the set of form-lengths from the superposed strips.

9. A manifolding pile comprising a plurality of continuous worksheet strips each having a succession of forms or sheet lengths separated by lines of perforations; a continuous carbon sheet interleaved between each two adjacent worksheet strips; staples located at intervals along the pile of superposed strips at the lines of perforations for securing all of the strips of the pile together in desired relation with the lines of perforations of the several strips in registration, until the pile is severed along said lines; other staples located at intervals along the pile of strips for securing less than the total number of strips together in desired relation, said other staples being located between the successive lines of perforations so as to hold certain of the worksheets and interleaved carbon collated together subsequent to the severance of the set of form-lengths from the superposed strips; and other lines of perforations in the worksheets constituting the group which is secured together by the second-named staples on which lines the latter are located and along which said worksheets may be torn from the staples.

10. A manifolding pile comprising a plurality of continuous worksheet strips each having a succession of forms or sheet lengths separated by

lines of severance; a continuous carbon sheet interleaved between each two adjacent worksheet strips; staples located at intervals along the pile of strips for securing the said strips together in desired relation, said staples being located between the successive lines of severance so as to hold the worksheets and interleaved carbon collated together subsequent to the severance of a set of form-lengths from the superposed strips; and short lines of perforations in the said worksheets which are secured together by the staples on which the latter are located and terminating a short distance from the both sides of the staples along which said worksheets may be torn from the staples.

11. A manifolding pile comprising a plurality of continuous worksheet strips each having a succession of forms or sheet lengths separated by lines of severance; a continuous carbon sheet interleaved between each two adjacent worksheet strips; staples located at intervals along the pile of strips for securing the said strips together in desired relation, said staples being located between the successive lines of severance so as to hold the worksheets and interleaved carbon collated together subsequent to the severance of a set of form-lengths from the superposed strips; and lines of perforations in the said worksheets which are secured together by the staples on which the latter are located and along which said worksheets may be torn from the staples.

12. A manifolding pile comprising a plurality of continuous worksheet strips each having a succession of forms or sheet lengths separated by lines of severance; a continuous carbon sheet interleaved between each two adjacent worksheet strips; means located along the pile of strips for securing less than the total number of strips together in desired relation, said means being located between the successive lines of severance so as to hold certain of the worksheets and interleaved carbon collated together subsequent to the severance of the set of form-lengths from the superposed strips; and sheet weakening means on the worksheets whereby one of said worksheets may be separated from the others.

13. A manifolding pile comprising a plurality of continuous worksheet strips each having a succession of forms or sheet lengths separated by lines of severance; a continuous carbon sheet

interleaved between each two adjacent worksheet strips; staples located at intervals along the pile of strips for securing the said strips together in desired relation, said staples being located between the successive lines of severance so as to hold the worksheets and interleaved carbon collated together subsequent to the severance of the set of form-lengths from the superposed strips; and lines of perforations extending across said worksheets from edge to edge and located between said staples and the ends of the forms along which the form may be torn to permit its removal from the set held together by the staple, the portion of the worksheet remaining constituting a stub which remains engaged by the staple.

14. Superposed record strips and interposed carbon strips divided at intervals by registered weakening lines to form successive sets of record and transfer sheets, at least two of the record sheets of a set each having a supplementary weakening line forming a marginal detachable portion, the sheets of a set being fastened together by securing means located within the boundaries of said detachable portion.

15. Superposed record strips and a transfer strip between the adjacent record strips, said strips being divided into successive manifolding sets of sheets by transverse registered weakening lines, fastening means securing said set of sheets together along an edge thereof, selected ones only of said sheets having supplementary weakened severance lines extending parallel with and adjacent said secured edge of the set of sheets and forming homologous sheet edges when severed along said lines, while the remaining sheet or sheets have unweakened portions in line with said supplementary lines of severance.

16. Superposed record strips and interleaved transfer strips divided at intervals by registered transverse weakening lines to form sets of interleaved record and transfer sheets, selected ones only of said sheets having at one edge of the set of sheets finger-grip areas extending inwardly from said edge of the set of sheets and defined by lines of severance including a weakened severing line while the remaining sheet or sheets of the set are free of such lines of severance at corresponding parts thereof, and fastening means located in said finger-grip areas for securing the sheets of the set together.
